Loy E. Barton,
BY *W. Goldsborough*
ATTORNEY.

The sole function of the diode rectifier 3 is to increase the negative bias on the control grid 13 of the pentode section when energy is impressed upon the amplifier input circuit. Since 5 a flow of current through the diode rectifier causes the upper end of the resistor 51 to become negative, the control grid 13 also becomes more negative because of its connection to the negative end of the resistor 51 through a high impedance resistor 53.

10 The self biasing resistor 49, the resistor 51 and the plate resistor 37 are preferably shunted by condensers 55, 57 and 59, respectively, for bypassing alternating current having the frequency of the input voltage.

15 It will be apparent from the foregoing description that as soon as an alternating control voltage is impressed upon the input circuit of the pentode 9, the control grid 13 of the amplifier 20 becomes more negative because of the current flow through the circuit of the diode.

25 It should be noted that the change in bias on the control grid 13 depends, to a certain extent, upon the voltage drop produced in the self-biasing resistor 49, since this voltage drop is in series with the voltage drop along the resistor 51 of the diode circuit. That these voltage drops are in series will be made evident by tracing the direct current path of the pentode section input 30 circuit. It may be traced from the control grid 13 through the secondary winding 25, the high impedance resistor 53, through the diode circuit resistor 51 to ground, through ground to the self-biasing resistor 49, and through the self-biasing resistor 49 to cathode 7.

35 When there is no alternating voltage being impressed upon the amplifier input circuit, the plate current of the pentode 9 is large, since the only negative bias on the control grid 13 is that due to the self-biasing resistor 49, and this negative bias is comparatively small. Consequently, there is a large voltage drop in the plate resistor 37, whereby the upper end of resistor 37 is at a comparatively low positive potential with respect to ground. This potential may be supplied 40 through an output circuit 61 to a circuit or device (not shown) to be controlled by the alternating voltage input. At the same time, the gain of the pentode 9 is low because of the low voltage on its anode 19.

45 As soon as an alternating voltage is impressed upon the input circuit, the amplifier 9 supplies signal energy to the diode 3, the voltage drop in the diode circuit resistor 51 increases the negative bias on the control grid 13, whereby the plate current of amplifier 9 decreases and the upper end of the plate resistor 37 becomes more positive with respect to ground. Thus a higher voltage is applied to the output circuit 61. It will be apparent 50 that, at the same time, a higher voltage is applied to the anode 19 of the pentode.

55 It should be noted that although the decrease in plate current tends to cause a reduction in the biasing voltage drop across the self-biasing resistor 49, the increased negative bias provided by the current flow through the diode circuit resistor 51 is much greater than any decrease in bias due to reduction in plate current.

60 The above described action of the diode-pentode 70 circuit whereby the upper end of plate resistor 37 becomes less negative in response to a voltage impressed upon the input circuit is preferably made a "trigger" action by giving plate resistor 37 a proper resistance value. This "trigger" action depends upon the fact that the increase in gain

caused by the increase in the plate voltage is greater than the decrease in gain caused by the increase in negative bias on the grid. In practice, a tube of the type known as RCA 2B7 has been found satisfactory for use as the tube 1.

5 Figure 2 shows a family of plate curves for a particular vacuum tube having the characteristics which are preferred in practicing my invention. The operation of my amplifier will be better understood by referring to the load lines R_1 and R_2 10 drawn through the plate curves, the load line R_1 being for a plate load of 25,000 ohms and the load line R_2 being for a plate load of 50,000 ohms. For the purpose of explanation, it will be assumed that the plate load is equal to the resistance value of 15 the plate resistor 37.

20 Under the condition of no input voltage to the amplifier, there is only a small negative bias on the control grid 13 and the plate current is correspondingly high, whereby the voltage drop in resistor 37 is so great that the pentode 9 is operating at a very low plate voltage. At this low plate voltage the amplification of the pentode is comparatively low, as will be seen by referring to the intersection of the load line R_1 with the plate 25 curve for a bias voltage of minus one volt. It will be apparent that, if the voltage impressed upon the input circuit swings the grid one volt each side of the bias potential, that is, between zero volts and minus 2 volts, there is a comparatively small 30 change in the plate voltage, as indicated by the spacing between vertical lines 63, 65 and 67.

35 As previously explained, the input voltage causes the negative bias of the grid 13 to increase. Assuming the input voltage has increased the bias to minus 3 volts, it will be seen, by referring to the spacing between vertical lines 67, 69 and 71, that a grid swing of one volt each side of the bias voltage causes a greater change in plate voltage than was caused by the same grid swing at the 40 lower bias potential. A further increase in negative bias on the control grid 13 causes the tube amplification to increase still further and the output voltage may increase very rapidly (depending upon time constants of the circuits of condensers 45 59 and 29) up to a certain point. The curves show that as the bias increases to some value beyond the region minus of 5 volts, the change in plate voltage for a given grid swing begins to decrease, that is, the amplification of the pentode 50 9 begins to decrease. In other words, at this point the increase in amplification due to the increase in plate voltage becomes less than the decrease in amplification due to the increase in negative bias on the control grid, and the amplifier has reached 55 a stable condition where the output voltage is a maximum.

60 The operation of the amplifier along the load line R_2 is the same as described above except that for the higher load resistance a greater voltage input is required to "trigger" off the amplifier. This is because a given input will cause a smaller change in plate voltage than in the case where a smaller load resistance is used, as will be apparent from the curves.

65 It will be understood that in place of the double tube shown in Figure 1, separate pentode and diode tubes may be employed.

70 Various other modifications may be made in my invention without departing from the spirit and scope thereof and I desire, therefore, that only such limitations shall be placed thereon as are necessitated by the prior art and set forth in the appended claims.

I claim as my invention:

1. In combination, an electric discharge device having an input circuit and an output circuit, said device having a plurality of electrodes including a control grid and an anode and having the characteristic that at low anode voltages its gain increases with increase of anode voltage, means for applying a negative bias to said control grid means for increasing said negative bias in response to an increase in alternating voltage applied to said input circuit, and a resistor in said output circuit in series with said anode whereby the anode voltage increases as said control grid becomes more negative. 5
2. In combination, an electric discharge device having an input circuit and an output circuit, said device having a plurality of electrodes including a control grid and an anode and having the characteristic that, over a certain voltage range, the gain of said device increases with increase in voltage applied to said anode, a resistor in series with said anode, and means for making said control grid more negative in response to an increase in alternating voltage applied to said input circuit whereby the voltage applied to said anode is increased, said device having the further characteristic that over said certain range the decrease in gain caused by said control grid becoming more negative is less than the increase in gain caused by the resulting increase in anode voltage. 10
3. In combination, an electric discharge device having an input circuit and an output circuit, said device having a plurality of electrodes including a control electrode and an anode and having the characteristic that, over a certain voltage range, the gain of said device increases with increase in voltage applied to said anode, a rectifier having an input circuit and an output circuit, said rectifier input circuit being coupled to said first output circuit, said rectifier output circuit being so coupled to said first input circuit that said control electrode becomes more negative in response to an increase in the alternating current output of said discharge device, a resistor in series with said anode, and means for coupling a work circuit to said resistor. 15
4. Apparatus according to claim 3 characterized in that said discharge device has the further characteristic that over said certain range the decrease in gain caused by said control electrode becoming more negative is less than the increase in gain caused by the resulting increase in anode voltage. 20
5. A trigger amplifier comprising a vacuum tube of the suppressor grid type, said tube having a plurality of electrodes including a control grid and an anode, said tube having an input and an output circuit, a rectifier, means including said rectifier for giving said control grid a negative bias which increases in response to an increase in alternating current output appearing in said output circuit, and means in the anode circuit of said tube for increasing the voltage applied to said anode in response to a reduction in the plate current of said tube. 25
6. An amplifier according to claim 5 characterized in that the voltage applied to said anode has a value such that an increase in said voltage causes an increase in the gain of said tube. 30
7. In combination, an electric discharge device having a plurality of electrodes including a pair of principal electrodes and a third electrode, means for producing a direct current flow be- 35
- tween said principal electrodes, means for applying a biasing potential to said third electrode in accordance with a flow of alternating current between said principal electrodes whereby said direct current flow is varied, and means for controlling the voltage across said principal electrodes in accordance with said direct current flow. 40
8. In combination, an electric discharge device of the pentode type having a pair of principal electrodes, a control grid, and two auxiliary grids, means for producing a unidirectional current flow between said principal electrodes, an input circuit connected to said control grid and one of said principal electrodes whereby an alternating voltage impressed upon said input circuit will produce an alternating current component in said unidirectional current flow, means for applying a biasing potential to said control electrode in accordance with said alternating current component whereby the direct current component of said unidirectional current flow is varied, and means for controlling the voltage across said principal electrodes in accordance with said direct current component. 45
9. In combination, an electric discharge device of the pentode type having a pair of principal electrodes, a control grid, and two auxiliary grids, means for producing a unidirectional current flow between said principal electrodes, an input circuit connected to said control grid and one of said principal electrodes whereby an alternating voltage impressed upon said input circuit will produce an alternating current component in said unidirectional current flow, means for biasing said control grid an increasingly negative amount in response to an increase in said alternating current component whereby the direct current component of said unidirectional current flow is decreased, and a resistor connected in series with said principal electrodes whereby the voltage applied across said principal electrodes increases with decrease in said direct current component. 50
10. In combination, an electric discharge device having a plurality of electrodes including a pair of principal electrodes and a third electrode, said device having pentode characteristics, means for producing a direct current flow between said principal electrodes, means for applying a biasing potential to said third electrode in accordance with a flow of alternating current between said principal electrodes whereby said direct current flow is varied, and means for controlling the voltage across said principal electrodes in accordance with said direct current flow. 55
11. In combination, an electric discharge device having a plurality of electrodes including a pair of principal electrodes and a third electrode, said device having the characteristic that its curve of plate current plotted against plate voltage is concave downward, means for producing a direct current flow between said principal electrodes, means for applying a biasing potential to said third electrode in accordance with a flow of alternating current between said principal electrodes whereby said direct current flow is varied, and means for controlling the voltage across said principal electrodes in accordance with said direct current flow. 60
12. A trigger amplifier comprising a vacuum tube having an amplifier section and a rectifier 65
- 70
- 75

section, said amplifier section including a control electrode and having a plate circuit including a series resistor, a biasing circuit including said rectifier section, means for transferring energy from said plate circuit to said biasing circuit, and means including a resistor in said biasing circuit for increasing the negative bias of said control

grid in response to an increase in the transfer of energy from said plate circuit to said biasing circuit, said amplifier section having the characteristic that its amplifying ability increases with an increase in plate voltage.
